DECANTER OR SIMILAR ARTICLE

Oscar Jacob, 453 S. Los Palmas Ave.,
Los Angeles, Calif. 90005

Filed Sept. 27, 1968, Ser. No. 13,753

Term of patent 3½ years

Int. Cl. D9—01

U.S. Cl. D9—73

FIG. 1 is an elevational view of a decanter or similar article showing my new design;

FIG. 2 is an elevational view looking from the right of FIG. 1;

FIG. 3 is a bottom plan view; and

FIG. 4 is a top plan view thereof.

I claim:

The ornamental design for a decanter or similar article, as shown.
